UNITED STATES PATENT OFFICE.

THOMAS CHARLES WILLIS PULLINGER, OF DUMFRIES, SCOTLAND, ASSIGNOR OF ONE-HALF TO SIR WILLIAM BEARDMORE, BARONET, OF PARKHEAD, GLASGOW, SCOTLAND.

CONSTRUCTION OF WATER-JACKETED ENGINE-CYLINDERS.

1,301,740.

Specification of Letters Patent. Patented Apr. 22, 1919.

Application filed April 4, 1918. Serial No. 226,735.

To all whom it may concern:

Be it known that I, THOMAS CHARLES WILLIS PULLINGER, a subject of the King of England, residing near Dumfries, Scotland, 5 Great Britain, have invented certain new and useful Improvements in the Construction of Water-Jacketed Engine-Cylinders, of which the following is a specification.

This invention is for improvements in or 10 relating to the construction of water-jacketed engine-cylinders, and has for its object to provide a light construction of water-jacketed engine, the invention having particular reference to the method of making the joint between the jacket and the part carrying the same.

According to this invention, the engine-cylinder has rigid with it an outwardly-projecting shoulder at one end which shoulder faces toward the other end of the cylinder, and the water-jacket has a corresponding internal shoulder at that end and a portion which extends beyond the said shoulder to engage the side face of the shouldered 25 portion on the engine-cylinder in order that it may be secured to the cylinder-portion by such extension, for the purpose of holding the jacket "in" endwise against the end-thrust of packing placed between the two shoulders.

Preferably the end of the jacket not secured as described above, is provided with a gland for packing which bears against a circular portion rigid with the engine-cylinder. 35

In the accompanying drawings which illustrate one method of carrying out this invention:—

Figure 1 is an elevation in part section of 40 a cylinder-block with jacket attached;

Fig. 2 is a vertical section through the block of cylinders at right-angles to the section shown in Fig. 1 and centrally with one of the cylinders, and

Fig. 3 is a plan of the gland-plate for closing the lower end of the jacket.

Like reference letters indicate like parts throughout the drawings.

The block of cylinders shown in the drawing 50 comprises the usual head A into which are secured by any convenient means cylinders A¹ which may be of forged steel. The head projects laterally beyond the cylinders at A² and in this project-

ing portion a continuous shoulder A³ is provided which extends around the whole head and faces in the direction of the ends of the cylinders remote from the head. 55

A sheet-metal water-jacket B conveniently of steel is provided with a shoulder B¹ corresponding to the shoulder A³ on the cylinder-head and beyond this shoulder is an extension B² which is shaped to fit around the projecting portion A² of the head which, as indicated, extends around the entire block. 60

Between the shoulders A³ and B¹ a rubber packing-ring C is placed and in assembling the parts, the water-jacket is thrust endwise against this packing so that the packing is compressed and when so compressed the jacket is secured to the head by screws B³ which extend through the portion B² of the jacket and engage the part A² of the head. A water-tight joint is thus provided by the packing C between this end of 70 the water-jacket and the head of the cylinder-block.

The other end of the water-jacket is closed by a plate D shaped to fit the jacket and which may be secured thereto by welding. 80 In this plate holes D¹ are provided one for each cylinder, so that the cylinders project therethrough and that portion of each cylinder-wall which lies opposite the plate D is thickened as at D², say, by securing a piece 85 of metal around it, for example by welding a band thereon, and this thickened portion has its outer face turned true. The wall of each hole D¹ is recessed and screwthreaded as at D³ to receive a ring-nut D⁴. 90

In assembling the parts a rubber packing-ring D⁵ is placed in each recess provided in the wall of each hole D¹. A compression-ring D⁶ is then inserted and the ring-nut D⁴ screwed home so that the packing-ring is forced inward against the wall of the cylinder thereby forming a watertight joint between the cylinders and this end of the water-jacket; the faces of the parts bearing against the packing-ring are sloped to drive 100 the ring inward.

What I claim as my invention and desire to secure by Letters Patent is:—

The combination with a cylinder-block wherein the head end is provided with a 105 continuous outwardly-projecting shoulder which faces toward the other end of the cylinders, of a water-jacket surrounding all the

cylinders, having a corresponding internal shoulder at the head end, a portion which extends beyond the said internal shoulder to engage the side face of the shouldered portion on the cylinder-block, the bottom of the water-jacket being filled in with a plate provided with holes to permit the extension

through it of the cylinders and glands secured in the plate and engaging circular exterior faces which are circumferential to the 10 cylinders, substantially as set forth.

In testimony whereof I affix my signature.

THOMAS CHARLES WILLIS PULLINGER.
